UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAY-BOLT STRUCTURE.

1,295,871..

Specification of Letters Patent.

Patented Mar. 4, 1919.

Application filed May 3, 1918. Serial No. 232,815.

To all whom it may concern:

Be it known that I, ETHAN I. DODDS, a citizen of the United States, and a resident of Pittsburgh, in the county of Allegheny and State of Pennsylvania, have invented certain new and useful Improvements in Stay-Bolt Structures; and I do hereby declare the following to be a full, clear, and exact description of the invention, such as will enable others skilled in the art to which it appertains to make and use the same.

This invention relates to improvements in staybolt mountings for boilers,—the object of the invention being to provide simple and efficient means whereby the cap or closure for that type of mounting in which the head of the staybolt has its bearing in a part rigid with the boiler sheet, may be quickly removed to permit access to the head of the staybolt for testing purposes.

With this and other objects in view, the invention consists in certain novel features of construction and combinations of parts as hereinafter described and pointed out in the claims.

In the accompanying drawings, Figure 1 is a sectional view showing an embodiment of my invention, Fig. 2 is a transverse section, and Fig. 3 is a view of a modification.

1 represents a boiler sheet having an opening 2 and the metal around this opening is forced or pressed outwardly so as to form an integral boss 3 having its inner face curved as at 4 to form a bearing for the rounded or spherical head 5 of a staybolt 6. This boss is provided at or near its outer end with external segmental shoulders 7 and the end of the boss affords a seat 8 for the edge portion of a partly spherical cap 9,—

40 the internal configuration of the latter being such as to afford suitable clearance 10 for the head of the bolt.

The cap 9 is provided with a peripheral flange 11 which encircles the shouldered outer end of the boss 3 and said flange is provided at its inner edge with inwardly projecting segmental shoulders 12 to engage

behind the segmental shoulders 7 on the boss and secure the cap firmly to the latter. By turning the cap 9 (with the use of a suitable wrench) until the shoulders 12 shall have moved out of alinement with the shoulders 7 of the boss, said cap may be at once removed from the boss to expose the head of the staybolt for testing purposes.

In the form of the invention shown in Fig. 3 the integral boss 13 is provided internally with segmental shoulders 14 and the cap 15 (which may be formed with an angular exterior portion to receive a wrench) enters said boss and is provided with external segmental shoulders 16 to engage behind the segmental shoulders 14 of the boss.

Having fully described my invention what I claim as new and desire to secure by Letters-Patent, is:

1. The combination of a boiler sheet having an integral boss affording a bearing for the head of a staybolt and provided near its free end with segmental shoulders, and a cap for removably closing the outer end of said boss and provided with segmental shoulders to engage the segmental shoulders of the boss.

2. The combination of a boiler sheet having an integral boss affording a bearing for the head of a staybolt and provided externally with segmental shoulders, and a cap having a bearing on said boss and closing the outer end of the latter, said cap having a peripheral flange encircling the shouldered portion of the boss and provided with inwardly projecting segmental shoulders to engage behind the segmental shoulders of the boss.

In testimony whereof, I have signed this specification in the presence of two subscribing witnesses.

ETHAN I. DODDS.
